UNITED STATES PATENT OFFICE.

JAMES BROWN STANWOOD, OF CINCINNATI, OHIO.

FEED-WATER HEATER.

1,237,722.

Specification of Letters Patent. Patented Aug. 21, 1917.

Application filed January 2, 1915. Serial No. 77.

To all whom it may concern:

Be it known that I, JAMES BROWN STANWOOD, a citizen of the United States, and residing at Cincinnati, in the county of Hamilton and State of Ohio, have invented a new and useful Improvement in Feed-Water Heaters, of which the following specification is a full disclosure.

My invention relates to an improvement in feed water heaters and purifiers.

The objects of the invention are to produce certain, new and useful structural features and combinations, having characteristics coördinating to improve the efficiency and economy of operation; the embodiment being of superior structural simplicity and convenient usage.

The features of the invention are more fully set forth in the description of the accompanying drawings, forming a part of this specification, in which:—

Figure 1 is a central vertical section.

Fig. 2 is a top plan section on line 2—2, Fig. 1.

Fig. 3 is a bottom plan view.

The cylinder 1 is the water heater and purifier, enveloped by a shell 2, providing a heating jacket for the cylinder. The lateral jacket space is divided into a steam inlet compartment 3, and outlet compartment 4, by means of the diametrically disposed vertical partitions 5, 6, the ports 7, 8, being the inlet and outlet ports respectively. These partitions stop short of both the top and bottom of the shell, then from the inlet the steam flows longitudinally of the shell in opposite directions, thence over the top and bottom of the cylinder to the outlet at an opposite side.

Steam will also surround the upper marginal portion of the cylinder, occupying the restricted space defined by the converging portions of the cylinder and shell heads 9, 10, respectively. The upper head 10 of the shell is a dished annulus, the flange rim of which is interiorly united to the sides of the shell, and having a central manhole orifice. The cylinder upper head 9 is marginally arched, the outer periphery being secured to the sides of the cylinder, the inner periphery being the downturned flange 11, the coincident orifices of the heads constituting the upper manhole. The inner peripheries of the heads converge and at their point of convergence are secured together by rivets 12. The manhole plate 13

closes the opening defined by the extremity of flange 11, within the cylinder, being exteriorly removably supported by the arch brackets 14 and bolts 15. The bottom heads 16 and 17 of the cylinder and of the shell are likewise secured respectively to the walls of the cylinder and shell, the cylinder head margin being curved downwardly and inwardly, and secured to the shell head at 65 their line of convergence by rivets 18. The central orifices of the bottom heads form a bottom manhole which is sealed by the manhole plate 19, seating on the upturned flange 20 and supported by brackets and 70 bolts as at the top. The top and bottom openings are in vertical registration.

This unitary structure is vertically supported by a frame 21. The water inlet 22 in the bottom of the cylinder at one side 75 of the manhole, terminates in a rectilineal fitting 23 on the floor of the cylinder having outlets 24 at the T-couplings of the pipe sections constituting the fitting, discharging streams of water tangentially toward the 80 sides of the cylinder from different points around the manhole and preferably in proximity to the heated walls of the cylinder. The water outlet 25 is at the top of the cylinder, approximately over one branch of the 85 inlet fitting. A safety valve 26 is preferably provided for the heater.

In the jacket space adjacent the steam inlet and outlet ports are preferably placed angle-iron baffle plates 27, 28, for separating 90 oil, irrespective of the direction of steam flow, which may be drained at the bottom of the jacket through the draw-off 29. The cylinder may be drained through a draw-off 30 in the bottom head 16 thereof. 95

Preferably, and as shown in Fig. 3, the cylinder head opening is oval, its greatest diameter being smaller than the diameter of the circular opening of the shell head, thus exposing a marginal portion of the 100 interior periphery of the shell head, the cylinder opening being straddled by the arch brackets, the ends of which are seated on said exposed marginal portion of the shell head. 105

The water when introduced into the cylinder through the several discharge nozzles or outlets 24, is directed against the heated cylinder wall, and in such direction to induce spiral currents upon and around the 110 cylinder. The currents subside toward the center of the cylinder. Thus the incoming

water in an active state whirls within the highest heat zone of the cylinder and becomes relatively passive toward the center of the cylinder, approximately establishing 5 a dead water core into which the impurities are induced, so as to descend upon the base of the cylinder. The heated water is taken from the cylinder at its upper portion which contains the hottest water portion and where 10 the highest purification efficiency obtains.

The upper manhole can be opened and the walls of the cylinder scraped while the steam is on, and the settled impurities can be removed when desired through the bottom manhole.

Having described my invention, I claim:—

1. A feed water heater and purifier comprising a cylinder, a shell enveloping the cylinder and spaced therefrom to provide 20 a steam jacket space for the cylinder, said cylinder at each end having a centrally apertured convex head and said shell at each end having a centrally apertured head, each tangent to its respective cylinder head, with which it joins at and around said 25 apertures, forming a jacket space at the opposite ends of said cylinder, and said apertures at each end forming a common opening into the cylinder, and a removable closure plate for sealing said opening.

2. A feed water heater and purifier comprising a heater cylinder and an enveloping shell spaced from the cylinder providing a steam jacket space, said cylinder and shell 35 provided with centrally apertured connected heads at each end, partitions longitudinally between the walls of the cylinder and shell providing compartments around the cylinder communicating at their ends, steam inlet and outlet ports formed in said shell and 40 relatively diametric to communicate, each with a respective compartment, said partitions defining a longitudinal steam flow around the cylinder, and said cylinder having 45 a water inlet at its base and an outlet at the upper portion.

3. A feed water heater and purifier comprising a heater cylinder and an enveloping shell providing a steam jacket for the cylinder, said cylinder at each end having a cen- 50

trally apertured convex head and said shell at each end having a centrally apertured head, each tangent to its respective cylinder head with which it joins at and around said apertures, forming a jacket space at the opposite ends of said cylinder, and said apertures at each end forming a common opening into the cylinder, a removable closure therefor, a water inlet pipe within and at the base of the cylinder extending around the head opening and provided with a plurality of discharge outlets, arranged to discharge streams of water against the cylinder, a water outlet at the upper portion of the cylinder, vertical partitions between the shell and cylinder dividing the jacket space into chambers communicating at their ends, and ports through said shell providing a steam inlet and outlet for said chamber.

4. A feed water heater and purifier comprising a heater cylinder and an enveloping shell providing a steam jacket, said cylinder at each end having a centrally apertured convex head and said shell at each end having a centrally apertured head, each tangent to its respective cylinder head with which it joins at and around said apertures, forming a jacket space at the opposite ends of said cylinder, and said apertures at each end forming a common opening into the cylinder, a removable closure plate therefor, a water inlet within and at the base of the cylinder extending around the head opening and arranged to discharge several streams of water against the cylinder, a water outlet at the upper portion of the cylinder, vertical partitions between the cylinder and shell dividing the jacket space into chambers communicating at their ends, ports through said shell and at relative opposite sides, providing a steam inlet and outlet, and longitudinal baffle plates in the jacket space at said ports.

In witness whereof, I hereunto subscribe my name, as attested by the two subscribing witnesses.

JAMES BROWN STANWOOD.
